WELL PUMP

George L. Thompson and Leo A. Cejka, Avenal,
Calif.

Application April 10, 1939, Serial No. 266,926

16 Claims. (Cl. 103—240)

Our invention relates to improvements in oil well pumping apparatus. More particularly our invention is operated by the use of compressed gas or other suitable fluid means. The primary object is the production of simple and dependable pumping means for pumping oil from deep or shallow wells more effectively than heretofore, and substantially without retarding the flow of oil from the oil bearing formation into the casing by a high liquid level or back pressure being held on the producing formation. Another object is to save injection gas consumption in the operation of the pumping apparatus and to operate the pumping apparatus without raising each slug of oil entirely to the surface of the ground before repeating the operation, whereby the capacity of the pump is greatly increased and the injection or lifting gas is greatly reduced. Another object is to provide an apparatus for pumping oil which is controlled entirely from the surface of the ground and which does not require the use of intricate valve mechanism. Still further objects are to avoid losses from friction and thus improve the efficiency of the pumping apparatus and to eliminate the use of packers.

Our invention preferably employs compressed gas or other fluid as a motivating medium by which the liquid in the well is forced to the surface, a suitable pump chamber being provided below or near the normal level of liquid in or near the bottom of the well and valve mechanism for controlling the operation of the pump which is directed from above the surface of the well. A particular feature of our invention is that the motivating fluid such as gas is transported to the bottom of the well near the work to be performed where it is applied for service with substantially no friction losses. Each individual charge or slug of oil or other liquid being lifted does not have to be followed to the surface by an excessive flow of gas to eliminate any chance of the liquid falling back into the well, which results in a limited capacity of the pump and excessive use of injection or lifting gas, because a check valve is installed immediately above the pump chamber and an intermittent force is imparted to the liquid above this point resulting in a continuous succession of comparatively short slugs being projected to the surface without need for waiting or filling time nor loss in efficiency. This system increases the relative capacity of the pump, decreases the quantity of injection or lifting gas needed per barrel and effects a more efficient production from the well.

Other advantages of our invention will be apparent from the following description.

In the accompanying drawings, forming part of this specification, Fig. 1 is a diagrammatic elevation showing our invention applied to an oil well, portions thereof being broken away and the diagram being of skeleton form; Fig. 2 is a vertical central section on a reduced scale of the reciprocating power ram which is used above the surface of the well in this plan for reciprocating the means by which the controlling valves in the well are actuated, but any type of valve control may be used to operate the pump in the well; Fig. 3 is a vertical central section on a reduced scale of a fragment of the apparatus showing one of the controlling valve mechanisms adjacent to and above the pump chamber; Fig. 4 is a continuation downwardly of Fig. 3, showing the automatic check valve mechanism which is employed below the mechanism shown in Fig. 4 in the well; Fig. 5 is a section taken on the line 5—5 of Fig. 4; Fig. 6 is a section taken on the line 6—6 of Fig. 4; Fig. 7 is a vertical section of an alternative construction of the mechanism shown in Fig. 4; Fig. 8 is a cross section taken on the line 8—8 of Fig. 7; Fig. 9 is a cross section taken on the line 9—9 of Fig. 7; Fig. 10 is a cross section taken on the line 10—10 of Fig. 7, and Fig. 11 is a diagrammatic view illustrating the relative positions of the slide valves by which the motivating gas is successively admitted into the pump chamber and whereby the pressure of the trapped fluid at the end of each stroke in the pump chamber is equalized with the pressure of the well formation fluid to permit the formation fluid to flow freely into and fill the pump chamber.

In Fig. 1 of the drawings, we have shown diagrammatically an equipment embracing our invention applied to an oil well. In this equipment, A is the usual surface string of casing which is set in the drill hole and cemented into the customary cellar 12, the latter being excavated in the surface of the ground below the derrick 13. B is a string of casing commonly referred to as the oil string, spaced freely from the inner surface of the casing, sealed at its upper end therefrom and extending downwardly into and held stationary in the bottom of the well. If any liner is used it is merely a continuation and a substitute of smaller diameter replacing the bottom of this casing. The upper end of this casing is closed and connected by the casing flow line or valved duct 14 of what is generally termed the Christmas tree, to the trap

18 for separating wet casing head gas and oil that is pumped from the well. C is what we have chosen to term the tubing or flow line for the liquid pumped from the well which is also held stationary in the well suspended from the Christmas tree internally between flow lines 14 and 17 and consists of a string of sectional pipes joined endwise together and extending downwardly to near the bottom of the well so that its lower end is submerged in the oil or other liquid to be pumped from the well. The upper end of this flow line tubing is sealed by the cap 16 (see Fig. 2) and connected through the Christmas tree by the flow line 17 with the trap 15. D is what we have chosen to term the gas line tubing which is composed of a string of macaroni tubing of comparatively small diameter, the sections thereof being joined endwise together in the usual manner and supported by the power piston 20. This tubing extends downwardly into the lower portion of the well and in this plan is reciprocated from above to operate pump controlling valve means in the well and in addition is employed to conduct gas or other fluid under pressure from above downwardly into the well to expel oil or other liquid from within the pump chamber to the surface above.

The gas line tubing in this plan is reciprocated by any suitable means, that shown consisting of a ram E, which is incorporated into a frame 18 (see Fig. 2), said frame being mounted upon the cap 16 on the pump tubing C. This ram has a vertical cylinder 19 and a piston 20, said piston serving to support the macaroni tubing D so as to raise and lower the latter as the piston reciprocates. Suitable glands 21, 22 and 26 and the bushing 26' produce tight working joints for the gas line tubing to slide through. The upper end of the cylinder carries the upright yoke 23 which has a stationary vertical tubular gas terminal chamber 24 into which any suitable motivating fluid such as compressed gas is admitted by the fluid duct 25 from any suitable source of supply such as a compressor (not shown). In actual practice we have employed gas under as high as 2000 pounds pressure for effectively pumping oil from a depth of over 8000 feet. The gas terminal chamber 24 allows the macaroni tubing to reciprocate freely therein and said gland 26 is provided in the yoke to produce a leak-proof joint. The upper end of the gas line tubing opens freely into the terminal chamber 24, thus making a free movable connection.

The power cylinder and its piston are located above the Christmas tree and can be motivated by any suitable means. In this plan we have employed mineral seal oil at substantially 125 pounds pressure or if the weight of the macaroni tubing is counterbalanced the pressure need only be 15 or 20 pounds. This oil is admitted to and bled from the cylinder by two small diaphragm regulators 27 and 28 through duct 60 and controlled by the variable intermitter 29. When desired other means for controlling the operating fluid to cause the reciprocation of the piston can be employed, such for illustration as electrical solenoid, slide, gate, globe or rotary valves, etc. (not shown), which constitute usual means for such purposes. The mineral seal oil is shown supplied from the receiver 30 resembling a gas trap half full of oil and half full of gas which is kept replenished and up to pressure by a small automatic pressure controlled pump 31 receiving negative pressure from a small open tank 32 into which the oil is returned from the power cylinder

19. However, any operating means can be used to reciprocate the gas line tubing if of sufficient pressure such as water from a main line, having a constant pressure, high pressure gas from the 5 injection gas compressor or main line, or mechanical means such as a walking beam or pumping jack, and these means of operating the control valves in the top and bottom of the pump chamber may be changed if desired as the 10 principal claim and advantage of this pump is the method of filling, emptying and relieving the pressure in the pump chamber proper.

Gas is compressed on the surface to whatever pressure is necessary to meet the depth and 15 productivity conditions and pumped into the string of gas tubing D. This tubing as shown is coaxially arranged and reciprocates vertically in the flow line, suitably passaged bearings 45 being secured in the flow line at proper intervals 20 for supporting and guiding the tubing and allowing free circulation of liquid through the flow line. The lower end of this tubing which projects downwardly below the level of the liquid in the pump chamber is shut off at the bottom by 25 the lower telescopic or slide valve F (see Fig. 4). Any suitable type of valve may be used at this location. This valve functions to successively 30 deliver compressed gas from the gas line tubing into the annular space G between the gas line tubing and the flow line tubing which forms the pump chamber. Each up stroke and each down stroke opens and closes the valve F respectively. The pump chamber fills with liquid through a 35 suction screen 33 on the lower end of the flow line tubing and through the pair of automatic standing check valves 34 and 35 which are coupled into the flow line tubing between the valve F and the screen 33. The valves 34 and 35 are 40 of usual gravity type employed in ordinary well pumps excepting that the casing of the upper ball valve 35 serves to hold a passaged cylindrical disc 36 (see Fig. 6) by its joint to the lower end of the flow line tubing and that said disc has an upwardly extending solid stationary stem 37 over 45 which the stationary ported tubing 38 of valve F is secured and the lower portion of the gas line tubing telescopes and reciprocates to open and close passages 39 and 39'. While valve F is 50 closed the pump chamber G fills with oil to the normal level of oil in the liner or casing B. When the pressures or liquid levels become equalized the standing valves 34 and 35 will close automatically by gravity. During this period it will 55 be noted that the injection gas to be admitted is stored under full compressor discharge pressure and shut off and the valve H at the upper end of the pump chamber G is open as shown in Fig. 3 and allows fluid rushing in through the lower check valves 34 and 35 to displace the vapors and all gas in the pump chamber G out through ports 39' into the annular space between the liner B and flow line tubing C and fill the pump chamber G completely with liquid. It is 60 contemplated that any type and any number of standing check valves may be used in place of the valves 34 and 35.

The upper control valve in this plan is reciprocated by the gas line tubing and is arranged to open and close port passages 39' through the 65 wall of the tubing C by which the oil bearing formation and the annular space between the flow line tubing C and casing is brought into communication with the pump chamber G lying between the walls of the gas line tubing and the flow line tubing. This valve H is composed of

inner and outer sleeves 40 and 41 which are spaced apart. The inner sleeve is secured by the annular key or lock ring 42 to the gas line tubing and the two sleeves are secured together at their opposite ends by the guide fins 55 and 56 which are annularly spaced apart to provide free passages through the pump chamber at valve H between the sleeves 40 and 41. Thus as the gas line tubing reciprocates the ports 39 are alternately opened and closed. The ports 39' in the flow line tubing C and the ports 39 in the gas line tubing D are so proportioned that the upward movement of the gas line tubing first closes port 39' and then opens port 39. Thus the pump chamber is first sealed before the injection gas is admitted at valve F.

An upper standing valve I is coupled to the flow line tubing at a suitable distance above the valve ports 39' and is provided with a sleeve 43 in which the gas line tubing reciprocates. This particular valve has a plurality of valve balls which open automatically by the increase of pressure from below or the upward rush of oil or other liquid or fluid during the admission of compressed gas into the pump chamber and close automatically when the supply of gas or the upward movement is checked. The intermitter 29 is so timed as to hold the ram and macaroni tubing in the upper position long enough to completely empty the pump chamber during each stroke. Then when the macaroni tubing is lowered it remains in the lowered position long enough to allow the trapped injection gas within the pump chamber G to escape through ports 39' and said chamber to completely refill again with liquid through valves 34 and 35. The lowering of the gas line tubing closes ports 39 of valve F (see Fig. 11) and then opens ports 39' of valve H, thereby relieving all pressure within the pump chamber outwardly through ports 39' into the annular space between the flow line tubing C and casing B. This relieves the injection gas which is trapped within the pump chamber and equalizes the same with that of the oil bearing formation. Gas can be produced from the casing through the flow lines and the regulator 46 therein at all times without interrupting or impairing the operation of the pump. Any type of check valve means may be employed in place of the valve I. The economical pressure to maintain upon the casing depends upon local conditions as this pressure is a direct back pressure on the oil producing formation and can be lowered to whatever pressure the oil bearing sand or the compressor plant facilities will permit without impairing the operation of the pump. As before stated any suitable means may be employed to deliver a slow succession of short pulsating vertical strokes to the gas line tubing. The means shown is adjustable thus permitting the operator to apply the operation of the ram according to the production capabilities of the well.

In the alternate construction shown in Fig. 7, the structure shown therein is intended to be substituted in place of that shown in Fig. 4. The functioning of the apparatus is substantially the same. The construction of the lower valve J is also the same except that the parts are enclosed by an enlargement at the upper end of the macaroni tubing for the purpose of transporting the injection gas on down to the bottom of the pump chamber. In this construction the gas line tubing D terminates and the end reciprocates in a ported stationary valve 48 which is

surrounded by an elongated enlarged duct 49 of the section of tubing 50 into which the lifting gas is admitted by the upward stroke of the gas line tubing. A gas deflector plate 52 is attached by four braces 53 to the lower end of the stationary portion of the macaroni tubing 50. The vents 51 are to provide an escape for all gas and vapors trapped within the tubing 50 and duct 49 while same and pump chamber are filling with liquid, also when the injection gas is admitted by the raising of the macaroni tubing these vents act as jets and help aerate the liquid from that point upwardly while the main gas body is forcing all of the liquid down and out of the tubing 50 and back up through pump chamber G as if the valve was at the bottom. Advantages attained by this alternative construction are that a larger pump chamber capacity is provided, a shorter spacing between the controlling valves is accomplished, and the pump can be confined within a casing or liner of smaller diameter than otherwise.

An outstanding feature of this invention is that by the proper spacing of the valves we veritably convert the bottom portion of the tubing or oil flow line into a pump chamber that can be varied in length. By the operation of the valves this pump chamber is actually equalized in pressure with the casing and surrounding formation and is filled with liquid by gravity, displacing all of the vapor or gas therein in one operation and is repressured and emptied into the tubing or flow line above the pump chamber and on its way out of the well in the next operation. These valves may be operated by solenoid or magnetic actuating valves or any other types of valves that will accomplish the same results as though there was a piston within this pump chamber that completely empties its entire length each operation.

Another feature of our invention is the expulsion of the full capacity of the pump chamber and relief of the pressure within the pump chamber by each stroke of the pump, thus enabling the pump chamber to again refill immediately while previous slugs are on their way out thus greatly increasing the capacity of the pump. In this invention the power required to reciprocate the macaroni tubing is only equal to that required to overcome the friction of moving the tubing and the two valves as the weight of the macaroni tubing can be counterbalanced when desired.

Among the advantages attained by our invention are the following:

1st. It is possible to take all of the pressure off the oil bearing formation or even pull a vacuum on same without impairing the operation of the pump because the pump chamber fills by gravity or by difference in liquid level inside to outside the pump chamber thus allowing the well to produce gas and oil or liquid at its utmost.

2nd. Due to the arrangement of the valves each slug does not have to be followed any further than out of the pump chamber and after the slug has been driven out of the pump chamber the injection gas is shut off and that trapped within is mechanically bled off and equalized with the formation pressure thus greatly reducing the quantity of repressing gas needed per barrel of liquid and speeding up the number of slugs per hour and the capacity to approximately four times the number possible with the present single slug intermitting gas pumps.

3rd. The pump will lift all of the liquid out of the average pumping well up to the capacity of the pump as fast as it accumulates in the well.

4th. All of the gas from the well can be produced through the casing if so desired.

5th. The use of the pump is not limited as to depth.

6th. The pump can be operated on approximately one half of the injection or repressing gas per barrel of liquid pumped.

7th. The full pressure from the discharge compressor is available at the bottom of the well and the pump chamber.

In accordance with the patent statutes, we have described the principles of operation of our invention together with the apparatus which we now consider to represent the best embodiment thereof but we desire to have it understood that the construction shown is only illustrative and that the invention can be carried out by other means and applied to uses other than those above set forth within the scope of the following claims:

We claim:

1. In well pumping apparatus, a flow line extending downwardly in the well to admit liquid thereto from the well formation, a gas line reciprocable in and cooperating with the flow line to form a pump chamber having a valved passage in its lower end for admitting liquid from the well formation therein, admission valve means controlled by the reciprocable movement of the gas line to successively admit gas under pressure and force a series of liquid slugs from the pump chamber upwardly in the flow line, and check valve means in the flow line for preventing the return movement of the series of slugs in the flow line.

2. Well pumping apparatus of the type set forth in claim 1, including means controlled by the reciprocable movement of the gas line for equalizing the pressure between the oil producing formation of the well and the liquid admitted into the pump chamber when the admission valve means between the gas line and pump chamber is closed.

3. Well pumping apparatus of the type set forth in claim 1, in which the movement of the gas line is caused by a ram near the surface above the well.

4. In well pumping apparatus, a pump chamber adapted to be submerged in the liquid in the lower portion of a well, valved inlet means for admitting liquid from the well into said chamber and checking its return movement, an egress flow line extending downwardly into the well and connected with said chamber having valved means for checking the return flow of liquid into said chamber, a movable impelling fluid line extending downwardly into the well, admission valve means actuated by the movement of said impelling fluid line to successively admit fluid under pressure and impel liquid from the pump chamber upwardly in the flow line, exhaust valve means also actuated by the movement of said fluid impelling line to successively open the pump chamber into the well formation near the end of each upward impulse of the impelling fluid in the pump chamber, and means for actuating said impelling fluid line to cause the functioning of said admission and exhaust valve means.

5. In well pumping apparatus, a pump chamber submerged to receive liquid from the producing formation in the well, a flow line con-

nected with said chamber for the ejection of slugs of liquid therefrom, a reciprocable admission gas line connected with said chamber for ejecting liquid received from the formation upwardly through the flow line, gas admission valve means adapted to eject by a series of fluid impulses a series of slugs of liquid received from the formation upwardly in said flow line, means for equalizing the pressures in said chamber and the well producing formation after each impulse delivered by the gas line, means for checking the return movement of slugs of liquid in the flow line, means above the well for reciprocating said gas line, and means for delivering compressed gas to said gas line.

6. In well pumping apparatus, a flow line extending downwardly into the liquid from the well formation to be pumped, a movable gas line extending downwardly in and cooperating with the flow line to form a pump chamber below the level of liquid to be pumped, check valve means for admitting liquid from the well formation into the pump chamber, valve means controlled by the movement of the gas line for causing gas under pressure to successively eject slugs of liquid from the pump chamber upwardly into the flow line, and means for preventing the return movement of the slugs of liquid in the flow line.

7. In well pumping apparatus, a casing extending downwardly into the oil bearing formation, a flow line extending downwardly in said casing into the liquid from the formation to be pumped, a movably mounted gas line extending downwardly in and cooperating with the flow line to assist in forming a pump chamber below the level of liquid to be pumped, check valve means for admitting liquid from the well formation into the pump chamber, valve means controlled by the movement of the gas line for admitting charges of gas under pressure below the charges of liquid admitted into the pump chamber and forcing a series of slugs of liquid upwardly in said flow line, valve means for preventing the return movement of the series of slugs of liquid into the pump chamber from said flow line, and valve means also controlled by the movement of the gas line for releasing exhaust from the pump chamber and equalizing the pressure within the pump chamber with that of the liquid from the well formation during each period when the gas controlling valve means is closed, whereby liquid from the producing formation is permitted to flow freely into the pump chamber substantially without building up a high liquid level or exerting back pressure upon the well formation.

8. In well pumping apparatus, an egress flow line extending downwardly into the liquid to be pumped from the well formation, an impelling fluid line also extending downwardly into said liquid and cooperating with said flow line to form a displacement chamber submerged in said liquid, check valve means for permitting liquid in the well to flow into the lower portion of said displacement chamber and preventing the return flow of said liquid from said chamber, admission valve means for intermittently releasing compressed fluid from the impelling fluid line into the lower portion of said chamber and forcing slugs of liquid from said chamber upwardly through said flow line, check valve means for preventing the return of said slugs of liquid into said chamber, exhaust valve means adapted to intermittently open said chamber into the well and equalize the pressure of fluid within the chamber with the pressure of liquid from the

well formation when the admission valve means is closed, said admission valve means and exhaust valve means being positively operated from the surface above the well to successively open and close.

9. In well pumping apparatus, a pump chamber submerged to receive liquid from the liquid bearing formation in a well, a valved fluid line connected with the pump chamber having means for intermittently admitting compressed fluid into said chamber and ejecting the contents thereof, a flow line extending upwardly from the pump chamber in which a series of slugs of liquid is ejected from the pump chamber by said intermittent flow of fluid, valve means for equalizing the pressures between the pump chamber and the producing formation after each effort of the fluid, and valve means for admitting liquid from the producing formation into the pump chamber while said pressures are equalized, the functioning of the valve means for equalizing pressures in the pump chamber and the well producing formation after each pulsating effort delivered by the fluid line being controlled by the mechanical movement of the fluid line.

10. In well pumping apparatus, a pump submerged to receive liquid from the liquid bearing formation in a well, a valved fluid line connected with the pump chamber having means for intermittently admitting compressed fluid into said chamber and ejecting the contents thereof, a flow line extending upwardly from the pump chamber in which a series of slugs of liquid is ejected from the pump chamber by said intermittent flow of fluid, valve means for equalizing the differential pressure between the pump chamber and the producing formation after each effort of the fluid, and valve means for admitting liquid from the producing formation into the pump chamber while the pressures are equalized, the functioning of the valve means for equalizing the pressures in the pump chamber and the well producing formation after each pulsating effort delivered by the fluid line being controlled by the reciprocable movement of the fluid line.

11. In well pumping apparatus, a pump chamber adapted to receive liquid from the liquid bearing formation in a well, a reciprocable gas line connected with the pump chamber, valve means for admitting compressed fluid from the gas line into the pump chamber to eject the liquid contents of the chamber, a flow line extending upwardly from the pump chamber in which a series of slugs of liquid is adapted to be ejected from the pump chamber by the compressed fluid, admission valve means freely movable in response to pressure conditions in the pump chamber and well for admitting liquid from the well into the pump chamber and checking return movement thereof, and means controlled by the reciprocable movement of the gas line for equalizing the differential pressure between the pump chamber and the liquid producing formation near the end of each lifting effort of the compressed fluid, whereby liquid from the liquid bearing formation may flow freely into the pump chamber through the admission valve means.

12. In well pumping apparatus, a pump chamber submerged to receive liquid from the liquid bearing formation in a well, a reciprocable gas line connected with the pump chamber to admit compressed gas and educt the contents of said chamber, means for controlling the admission of the compressed gas intermittently into the

5 pump chamber, a flow line extending upwardly from the pump chamber in which a pulsating stream of liquid is adapted to be ejected from the pump chamber by the action of the compressed gas, valved means controlled by the movement of the gas line and opening into the liquid bearing formation for equalizing the differential pressure between the pump chamber and the producing formation, valve intake means permitting the flow of liquid from the producing formation into the pump chamber while said pressures are equalized and checking return flow into the formation, and valve means for checking return flow of liquid in the flow line.

15 13. In well pumping apparatus, a pump chamber adapted to be submerged to receive liquid from the liquid bearing formation in a well, a reciprocable gas line connected with the pump chamber, means controlled by the movement of the gas line for admitting compressed gas into the pump chamber to successively eject the contents of said chamber, a flow line extending upwardly from the pump chamber in which a series of slugs of liquid is ejected upwardly from the pump chamber by said flow of gas, valve means controlled by the reciprocable movement of the gas line for equalizing the differential pressure between the pump chamber and the producing formation after each effort of the gas, and check 20 valve means for admitting liquid from the producing formation freely into the pump chamber while said pressures are equalized.

25 14. In well pumping apparatus, a pump chamber adapted to be submerged to receive liquid from the producing formation in a well, a flow line connected with said chamber for conducting slugs of liquid therefrom, a reciprocable gas line connected with said chamber for projecting liquid upwardly therefrom, a valve operable by the 30 strokes of the gas line for admitting pressure fluid to the pump chamber and controlling the flow of gas therethrough to successively eject a series of slugs of liquid received from the formation into said chamber upwardly in said flow line, 35 an exhaust valve for equalizing the differential pressure between said chamber and the producing formation after each stroke to permit said chamber filling freely with liquid from the producing formation, and means operable in synchronism with the functioning of said valves for preventing the return movement of the slugs of liquid in the 40 flow line.

45 15. In well pumping apparatus, a pump chamber submerged to receive a series of small solid slugs of liquid consecutively from the producing formation in a well, a flow line connected with said chamber for the eduction of the series of slugs of liquid therefrom, a reciprocable admission gas line connected with said chamber for propelling the slugs of liquid received from the formation upwardly through the flow line, admission valve means controlled by the movement of the gas line for admitting gas consecutively in short pulsations into the pump chamber to eject the series of short slugs of liquid received from the formation upwardly in said flow line, means operable in synchronism with the movement of the gas line for equalizing the differential pressure between said chamber and the producing formation after each pulsation of gas, and means for preventing return movement of the series of slugs of liquid from the flow line into the pump chamber.

50 16. In well pumping apparatus, an outer casing

adapted to extend downwardly into liquid in the well formation to be pumped, a flow line within said casing, a gas line movable in and cooperating with said flow line to form a pump chamber, check valve means controlling the admission of liquid from the well formation into the lower portion of the pump chamber, valve means controlled by the movement of the gas line for admitting compressed gas from the gas line into the pump chamber against each charge of liquid previously admitted, whereby the well formation

5 liquid is adapted to be forced upwardly through the flow line, valve means for automatically preventing return flow of liquid in the flow line, and means between the pump chamber and outer casing for equalizing the differential pressure between the pump chamber and well producing formation at the end of each impulse of the lifting gas admitted into the pump chamber.
